Rudolph C. Kulling, Chicago, Ill.

Application November 30, 1945, Serial No. 124,213

Term of patent 14 years

(Cl. D85—2)

To all whom it may concern:

Be it known that I, Rudolph C. Kulling, a citizen of the United States, residing at Chicago, in the county of Cook and State of Illinois, have invented a new, original, and ornamental Design for a Cigarette Butt Snuffer, or Similar Article, of which the following is a specification, reference being had to the accompanying drawing, forming part thereof.

Figure 1 is a side elevational view of a cigarette butt snuffer, or similar article, showing my new design,

I claim:

The ornamental design for a cigarette butt snuffer or similar article, as shown.

RUDOLPH C. KULLING.
